UNITED STATES PATENT OFFICE.

THOMAS BRENNAN, JR., OF MINNEAPOLIS, MINNESOTA, ASSIGNOR TO
MONITOR DRILL CO., A CORPORATION OF MINNESOTA.

SCRAPER FOR DRILL-DISKS.

No. 828,183.

Specification of Letters Patent.

Patented Aug. 7, 1906.

Application filed March 29, 1906. Serial No. 308,731.

To all whom it may concern:

Be it known that I, THOMAS BRENNAN, Jr., a citizen of the United States, residing at Minneapolis, in the county of Hennepin and State of Minnesota, have invented certain new and useful Improvements in Scrapers for Drill-Disks; and I do hereby declare the following to be a full, clear, and exact description of the invention, such as will enable others skilled in the art to which it appertains to make and use the same.

This invention relates to scrapers for drill-disks, and particularly to those employing spring-pressed arms having at their ends swiveled scraper-blades, and has for its object to improve the same in the several particulars hereinafter noted.

In the accompanying drawings, which illustrate the invention, like characters indicate like parts throughout the several views.

Referring to the drawings, Figure 1 is a view in side elevation, showing one of my improved scrapers applied to the boot and disk of a drill-disk, some parts being indicated in diagram only. Figs. 2 and 3 are details in plan, showing different sides of the scraper. Fig. 4 is a section taken on the line $x^4 x^4$ of Fig. 2, and Fig. 5 is a section taken on the line $x^5 x^5$ of Fig. 2.

1 indicates the boot, and 2 one of the disks, of a drill-disk, said parts being shown in diagram only.

3 indicates a scraper-equipped lever which is intermediately pivoted to a lug 4 on the seed-boot and the upper and forward end of which is yieldingly pressed outward in the usual or any suitable way, as by a coiled spring 3^a. Where the scrapers are arranged in pairs, the spring 3^a may work through an opening 1^a in the front flange of the boot 1 and may be pressed between the forward ends of two of the levers 3. When but one scraper is employed or when the scrapers are independently actuated, said spring 3^a may act against a suitable part of the boot.

The lever 3, near its lower and rearwardly-projecting end, is provided with a lock-flange 5, which is shown as segmental and is flattened on its upper edge, as shown at 5^a, for a purpose which will presently appear.

6 indicates a scraper-blade holder the ends of which are turned over or grooved at 7 to

form seats that are adapted to receive the edges of a flat longitudinally-tapered scraper-blade 8. At its central or intermediate portion the scraper-holder 6 is formed with a depressed part that affords an open seat 9 for the free and rounded end of the lever 3. This seat portion 9 is bifurcated or notched at 9^a to form a seat that is adapted to receive the lock-flange 5 of said lever, as best shown in Figs. 4 and 5. The scraper-blade 8 is formed with a lock-notch 8^a, that is also adapted to receive the lock-flange 5 when the parts are assembled.

The construction just described is such that when the blade 8 is turned into line with the flattened portion of the surface 5^a of the lock-flange 5 all parts of the said lock-flange 5 will be carried out of the notch 8^a of said blade, thus permitting the blade to be removed from the holder by endwise movement in the direction in which it flares.

As shown in Fig. 5 by dotted lines, the said blade can be moved into line with the said flattened surface 5^a only when it is turned into a horizontal position. In all other positions the said blade will be interlocked with the holder 6 by the said lock-flange 5. Otherwise stated, in all operative positions of the

blade 8 the said blade is interlocked with the blade-holder, so that it cannot be accidentally rattled or forced from said holder. It is also very important to note that the holder 6 cannot be removed from the lever 3 as long as the scraper-blade 8 is in working position therein. When the scraper-blade is removed from said holder, however, the said holder may be removed from said lever by lateral movement away from the open seat 9^a of said holder.

The lock-flange 5 of said lever therefore acts to lock the scraper-blade in the holder 6, and the scraper-blade in turn locks the holder to said lever in all positions except when the said blade is turned into a horizontal position, as shown by dotted lines in Fig. 5. With the flange described it is also possible to very quickly and easily reverse the scraper-blade 8 and holder simply by turning them pivotally on the said lever and without removing any of the parts from said lever. This feature is desirable because a scraper-blade when worn to a bevel on one side will not scrape a disk clean, but when

reversed occasionally may be used until it is worn too short for good work.

The scraper described may be very cheaply made and the parts thereof may be very 5 quickly assembled or taken apart.

I claim as my invention—

1. A scraper for drill-disks or the like, comprising a lever, a blade-holder swiveled on said lever, and a blade seated in said 10 holder, said blade and lever having interlocking engagement when said blade is in normal or operative position, substantially as described.

2. A scraper for drill-disks and the like, 15 comprising a lever having a lock-flange in the vicinity of one end, a blade-holder mounted for a swiveled movement on the flanged end of said lever, and a scraper-blade detachably seated in said holder and normally 20 interlocked with said holder, by the lock-flange of said lever, substantially as described.

3. A scraper-blade for drill-disks and the like, comprising a lever, a scraper-blade, and 25 a blade-holder, said scraper-blade and holder being swiveled on said lever, and means for locking said scraper-blade to said holder in both operative positions of said blade, but permitting said blade to be removed from 30 said holder when said blade is turned into an intermediate position, substantially as described.

4. A scraper for drill-disks and the like, comprising a lever, a blade-holder swiveled 35 on said lever, and a scraper-blade seated in said holder and holding the latter interlocked with but capable of swiveled movement on said lever, said holder being removable from

said lever when said scraper-blade is removed therefrom, substantially as described.

5. A scraper comprising a lever 3 having a segmental lock-flange 5 flattened at 5^a, a blade-holder 6 having blade-seats at its ends and having at its intermediate portion an open seat 9 with a slot 9^a, and a scraper-blade 8 45 fitting in the seats of said holder and having a notch 8^a alining with said slot 9^a, and which lock-flange 5^a works in said notch 8^a and said slot 9^a and holds said blade interlocked with said holder except when said 50 blade is turned into alinement with the flattened portion 5^a of said lock-flange, substantially as described.

6. The combination with a disk drill, of a spring-pressed lever pivotally connected to 55 the boot thereof, a blade-holder swiveled on said lever, and a scraper-blade seated in said holder, said blade having interlocking engagement with said lever when in normal or operative position, substantially as described. 60

7. The combination with a disk drill, of a spring-pressed lever pivotally connected to the boot thereof, said lever having a segmental or incomplete lock-flange at its free end, a blade-holder mounted for swiveled 65 movements on the flanged end of said lever, and a scraper-blade detachably seated in said holder and normally interlocked to said holder and lever by the lock-flange of the latter, substantially as described. 70

In testimony whereof I affix my signature in presence of two witnesses.

THOMAS BRENNAN, JR.
